INFLATABLE FOOTBALL SHOULDER CUSHION

Munro M. Grant, 3 Bluebell Ave., 212 Vanderbilt
Tower II, Naples, Fla. 33940

Filed Nov. 2, 1973, Ser. No. 412,183

Term of patent 14 years

Int. Cl. D2—02

U.S. Cl. D2—27

FIG. 1

FIG. 2

FIG. 3

FIG. 1 is a top plan view of an inflatable football shoulder cushion showing my new design;

FIG. 2 is a bottom plan view thereof;

FIG. 3 is an edge view; and

FIG. 4 is a front perspective view thereof, inflated, and in a position of use.

I claim:

The ornamental design for an inflatable football shoulder cushion, as shown and described.
